PENDANT CURTAIN WALL

George P. Reintjes, Kansas City, Mo.

Application September 2, 1952, Serial No. 307,411

5 Claims. (Cl. 110—1)

This invention relates to curtain walls or slot arches, 15 adjustable or fixed, for use with forging furnaces or as cut-off or curtain walls to divide car type furnaces in one or more units, and for use at other points where the construction may be advantageous. The wall is also adapted for use in open hearth furnaces and soaking pits or wherever damper control is desired in recuperative or regenerative systems or as a damper in flues in breathings for the stopping or retarding of gas flow.

One of the chief objects of the invention is to provide a curtain or link wall which is suspended on a metal support or grid, the wall preferably comprising side by side columns of refractory or tile having independent oscillation so that any intermediate section may swing if it is struck or contacts a load or a part of the furnace, without stressing or straining adjacent parts of the curtain wall.

Another object of the invention is to produce a curtain wall comprising independent sections which can be swung out for maintenance or repair, and is flexible to allow for warpage, expansion or contraction independently of adjacent sections of the wall.

A further object of the invention is to provide suspension means of such nature that the refractories can be made of the preferred material to suit the furnace operating conditions. Heretofore, in many curtain walls where the refractory was subject to tension it has been necessary to sacrifice high spawling characteristics in order to gain tensile strength. In other cases where refractory of high insulating property should be used, older methods of support would not permit their use because of their lack of strength. With the support of the invention, however, any type of refractory can be used, as each tile is preferably carried as a unit and high tensile strength is not necessary.

A still further object of the invention is to provide an oscillatory curtain wall which may be air or water cooled as may be necessary under the operating conditions encountered.

With the general objects named in view and others as will hereinafter appear, the invention consists in certain new and useful features of construction and organization of parts as hereinafter described and claimed; and in order that it may be fully understood, reference is to be had to the accompanying drawings, in which:

Figure 1 is a cross-section through a wall embodying the invention in which a chain is suspended from any overhead support, said chain carrying tile supporting clips at vertically spaced points.

Figure 2 is a face view of the wall as shown in Figure 1.

Figure 3 is an enlarged section to show the details of the hanger supporting the tile and the chain suspension.

Figure 4 is a view similar to Figure 1 in which a plurality of hangers are linked together to support the tile

2

or refractory and illustrating a port or passageway for the circulation of air for cooling purposes.

Figure 5 is a face view, partly in section, of the construction shown in Figure 4, together with a fragment 5 of a furnace wall.

Figure 6 is a perspective view of one of the special links for supporting each column of refractory.

Figure 7 is a perspective view of the link which supports the tile and forms the connecting member between 10 the links shown in Figure 6.

Figure 8 shows a wall embodying the invention, in combination with an overhead support and the side walls of a furnace.

Figure 9 is a reduced section through a furnace and a wall embodying the invention and illustrates in dotted lines the swinging out of a refractory column for repair or replacement, the position it may assume when it contacts an obstruction.

Figure 10 is a perspective view of the preferred type 20 of tile embodying the invention.

Figure 11 is a perspective view of the lowermost or bottom tile which is rounded off to offer less resistance to gas flow and to decrease danger of breakage if it hits an obstruction.

Figure 12 is a view similar to Figure 11 of a curtain 25 wall formed of book tile.

Figure 13 is a perspective view of an intermediate book tile used in Figure 12.

Figure 14 is a perspective view of the lowermost or 30 bottom book tile.

Figure 15 is a cross-section of a furnace wall as it 35 may appear when carried by water-cooled U-shaped tubes.

Figure 16 is cross-section through a similar wall in which water cooling is provided by a pair of pipes in telescoped position.

Figure 17 is a perspective view of a tile hanger which 40 may be used with either of the suspended pipe constructions.

In the said drawings, where like reference characters 45 identify corresponding parts in all of the figures, 1 is the side wall, 2 the roof and 3 the bottom of a furnace chamber. The curtain wall will be suspended by any suitable transverse support, such as a rotatable drum 4 or a beam 4a. With the drum 4, the wall may be supported by flexible chains or cables 5 for lifting purposes. In the drawings, three different types of oscillatory wall supports are illustrated, namely, Figure 1, a flexible chain; Figure 4, a specially designed link suspension; 50 and Figure 16, a pipe or rod suspension, each of these constructions being hereinafter more particularly described.

Where link chains 5, Figure 1, are to form the supports 55 for a series of flexible spaced independent columns of refractory forming a curtain wall, predetermined links support tile hangers 6 of saddle type and projecting by preference in opposite directions paralleling the axis of the overhead support. The saddle hangers are held in position by upwardly extending flanges 7 which are clamped by a bolt 8 to a superposed link of the chain.

Where a linked construction other than a chain is to be used, Figure 4, the links may comprise elongated castings 9 having slotted hook ends 10. Engaging the hook ends 10 of the castings 9 are socketed open hook portions 12 on the tile hangers 13 which are preferably designed to support a pair of tile. With the construction shown it will be evident that as long as the device is in tension the links and hangers are locked against accidental dislodgement by sidewise movement.

Where a construction is desired which is rigid, a rod 60 or pipe 23, Figure 16, may be used, said pipe being sus-

pended for oscillation as will hereinafter appear, by preference. In this construction the tile hangers 24 are welded or otherwise attached to the pendant or vertical support.

The refractories or tile 11 to be used with the supports shown in Figures 1, 4 and 16, are illustrated in Figures 10 and 11. The tile 11 is of generally rectangular form and has one of its faces provided with a longitudinal slot 14 which is intercepted adjacent one end by a socket 15 to receive the tile hanger. The lowermost tile of each column is preferably rounded as at 16 to eliminate sharp corners which are subject to spawling.

If desired, the suspended tile may be of "book" form as shown in Figures 12 through 14, so that the individual tile of each column may have rocking movement on the adjacent tile. Intermediate tile of this kind is shown at 17. This tile has a longitudinal slot 18 in one face which is flared at 19 above the hanger socket to accommodate the rocking movement in relation to superposed tile. The lowermost book tile 20 is also provided with a flared slot 21 above its tile hanger receiving socket 22 for permitting swinging movement of the tile as dotted in Figure 12.

Under some operating conditions it may be desirable to cool the refractory and metal supports by the circulation of gaseous or liquid cooling mediums. One means of circulating cooling air through the curtain wall is shown in Figure 4, where the lower tiles 16a are formed with transverse passageways 25. The longitudinal groove 14 of each tile communicates with the groove 25. One sidewall 2 of the furnace is formed with a through port 26 through which the air, under pressure or by gravity, is fed. By preference, a suitable packing 27 is inserted between the outermost column of tile and the furnace wall 2 as illustrated, but it will be noted that swinging movement of any tile column will interrupt air flow beyond the plane of such column. Of course, the cooling air may be omitted as indicated above, in which case the grooves 25 and ports 26 will not be used.

If fluid, such as water, is to be used as the cooling medium, the pipe support 23 may be capped as at 28 at its lower end. The upper end of the pipe is equipped with a two-way fitting 29 which is connected at one side to a water inlet flexible tube 30 which leads to the capped lower end of the pipe 23. Water is discharged by tube 30 circulates upwardly through the pipe 23 and out through a flexible connection 31 to a manifold 32 carried by the overhead support or beam 4a. Inlet tube 30 is fed from a supply manifold 33 also carried by beam 4a. One method of suspending the pipe for oscillation is to equip its fitting 29 with an eye 34, said eye receiving a U-bolt 35 carried by the beam 4a.

An alternate water cooled wall is shown in Figure 15, where pipe 36 is formed in a U-support. One leg of the U-support is connected by flexible tube 37 to a water feed manifold 38, and the other leg is connected by flexible tube 39 to an outlet manifold 40. The tile 41 and 42 as used in this construction are identical with those numbered 11 and 16, except their abutting faces are formed with parallel grooves to accommodate the two legs of the pipe. In this arrangement the upper ends of the U-pipe are attached to a cross-bar 42a which may be suspended for oscillation with an eye-bolt 43 and U-clip 44.

In considering the above description and drawings it will be apparent that the double pendant support for each tile as where the U-pipe is used, may be modified by substitution of a plurality of parallel chains 5 or links 9-10. This multiple suspension is particularly desirable with thick or high-refractory walls where the load on the oscillating support is fairly heavy as such multiple suspension divides the load between the pendant supports and lessens the tendency to yield or creep at high temperatures.

From the above description and drawings, it will be apparent that I have produced a construction embodying

all of the features of advantage set forth as desirable, and while I have described and illustrated the preferred construction, it is to be understood that I reserve the right to all changes within the spirit and scope of the appended claims.

I claim:

1. A furnace curtain wall comprising an elongated support having a horizontal axis, a pendant support mounted to the elongated support for swinging in a vertical plane at right angles to the axis of the elongated support, tile hangers vertically spaced lengthwise of the pendant support and projecting in opposite directions from said support at right angles to the plane of swinging movement, tile arranged in pairs with their upper and lower faces respectively contiguous to the lower and upper faces of adjacent pairs of tile and having matching vertical slots accommodating the pendant support, each tile having a socket laterally opening into the slot adjacent the upper end of the tile for suspending the tile from the hanger independently of adjacent tile.

2. A furnace curtain wall comprising an elongated support having a horizontal axis, a plurality of pendant supports equally spaced horizontally for independent swinging movement from the elongated support in parallel vertical planes at right angles to the axis of the elongated support, tile hangers vertically spaced lengthwise of each pendant support and projecting in opposite directions from the supports at right angles to the plane of vertical swinging movement, and tile arranged in pairs suspended from each hanger, each tile having a vertical slot accommodating the pendant support with laterally opening sockets in the slots receiving the hangers, with corresponding tile on adjacent supports in abutting relation when in vertical position and the tile on each pendant support having its upper and lower faces respectively contiguous to the lower and upper faces of adjacent tile, each tile column being free for swinging movement independently of adjacent tile columns.

3. A furnace curtain wall comprising an elongated support having a horizontal axis, a pendant metal support mounted for swinging movement on the elongated support in a vertical plane at right angles to the axis of the elongated support, and comprising alternate links and horizontally extending tile hanger members, each hanger having laterally opening hooks, and the opposite ends of the links having open hooks to be seated within the hooks of the tile hangers, whereby the hooks cannot be disengaged by sidewise movement as long as the support is subject to tension, and tile arranged back to back in pairs on said hangers, each tile having a slot accommodating the links with sockets laterally opening into the slots adjacent the upper end of the tile to receive the hangers whereby each tile is suspended from the hanger independently of adjacent tile, the upper and lower faces of each tile being contiguous to the lower and upper faces respectively of adjacent tile.

4. A suspended furnace wall comprising an elongated support having a horizontal axis, a vertically pendant linked metal member secured to the support for swinging movement at right angles to the axis of the support, said linked member alternately comprising tile hanger and suspension members, the latter being detachably secured to the tile hanger members, said tile hanger members projecting in opposite directions parallel to the axis of the support, and tile arranged in pairs back to back on said hangers, each tile having a vertical slot accommodating the metal link member with a socket laterally opening into the slot adjacent the upper end of the tile and receiving the tile hanger member, said tile pairs being arranged with their upper and lower faces respectively contiguous to the lower and upper faces of adjacent tile pairs.

5. A suspended furnace wall comprising an elongated support having a horizontal axis, a plurality of vertically pendant linked members secured to the support to swing

at right angles to the axis of the support, tile hangers secured in spaced relation to each linked member and projecting in opposite directions therefrom parallel to the axis of the support, and tile arranged in pairs back to back on the ends of each hanger, each tile having a vertical slot accommodating the linked member with a socket laterally opening into the slot and receiving the hanger member, said tile pairs being arranged with their upper and lower faces respectively contiguous to the lower and upper faces of adjacent pairs of tile.
